UNITED STATES PATENT OFFICE.

ERNEST H. SHAFF, OF GRAND HAVEN, MICHIGAN.

SUITCASE-LOCK.

1,265,534.

Specification of Letters Patent.

Patented May 7, 1918.

Application filed April 23, 1917. Serial No. 164,001.

To all whom it may concern:

Be it known that I, ERNEST H. SHAFF, a citizen of the United States, residing at Grand Haven, in the county of Ottawa and State of Michigan, have invented certain new and useful Improvements in Suitcase Locks, of which the following is a specification.

My invention relates to improvements in locks, and it consists in the constructions, combinations, and arrangements herein described and claimed.

An object of my invention is to provide a lock adapted more particularly for use upon suitcases, trunks, and the like, and it comprises a stamped metal body portion in which a spring pressed latch bolt is adapted to slide the distinguishing feature of the latch bolt being that a locking tumbler mounted thereon is first moved from engagement with an abutment on the body portion, and then the latch bolt is slid bodily in a lateral direction by pushing upon the locking key and thus effect the release of the hasp upon the suitcase.

Another object of the invention is to provide a lock for the purpose described, all of the constituent parts thereof being formed of pressed metal thereby facilitating the manufacture and assembling thereof.

Other objects and advantages will appear from the following specification, reference being had to the accompanying drawings, in which:

Figure 1 is a side elevation of a portion of a suitcase illustrating the application of my lock,

Fig. 2 is a cross-section on the line 2—2 of Fig. 1 looking in the direction of the arrow,

Fig. 3 is a cross-section on the line 3—3 of Fig. 1,

Fig. 4 is a detail plan view of the pressed metal body portion of the lock,

Fig. 5 is a detail perspective view of the slot cover,

Fig. 6 is an inverted plan view of the lock,

Fig. 7 is a similar view, parts of the latch bolt cover plate being shown in section,

Fig. 8 is a detail perspective view of the latch bolt,

Fig. 9 is a detail perspective view of the cover plate,

Fig. 10 is a detail perspective view of the key support which coöperates with the slot cover, and

Fig. 11 is a detailed perspective view of the spring operated hasp.

In the embodiment illustrated in Fig. 1 of the drawing, the lock is applied to the suitcase 1 which includes the usual hinged cover 2. A lock body or plate 3 is riveted upon the suitcase 1 as at 4. The lock body or plate 3 is formed of sheet metal and includes the flanges 5, the edges of which are adapted to rest upon the surface of the suitcase and thus serve to space the operating and carried parts of the lock therefrom.

The lock plate 3 includes a housing 6 which it will be observed from the drawings and particularly from Fig. 4, is also stamped upwardly from the lock plate 3. The housing 6 includes a circularly shaped stamped portion 7 which is centrally apertured as at 8. It will readily be understood that in forming the lock plate 3 the formation of the housing 6, the circular portion 7 and etc. are formed in one operation.

The housing 6 is provided with a pair of slits 9 between which a key opening 10 is disposed. The opening 10 may be more properly termed a key slot. The key-slot 10 is covered by a slot cover 11, which as will be seen from Fig. 5, consists of a rectangular body portion having a flange upon all of its edges, the opposite ones of the flanges being provided with tangs 12 which are adapted to be received by the slits 9.

The slot cover 11 illustrated more particularly in Fig. 5, is provided with a key hole 13. A key support 14 clearly shown in Fig. 10 includes a circular upstanding portion 15 which is movable in the circular portion of the key hole 13 of the slot closure or cover 11. It will be understood particularly from Fig. 1 wherein the slot cover 11 and the key support 14 are shown as being assembled, that a key when thrust into the key opening in the respective members 11 and 14, 100

that the key may be readily turned since the key support 14 will revolve beneath the cover 11.

5 A latch bolt 16 is movable in the housing 6 of the lock plate 3. The latch bolt 16 is also formed of stamped sheet metal and includes the side guides 17 which serve to space the latch bolt 16 from the housing 6 and also provide bearings for the latch bolt.

10 A lip 18 is formed at one end of the latch bolt 16 adjacent to an opening 19 in the edge of the latch bolt. The opening 19 permits the entrance of the tongue 20 on the hasp 22. The tongue 20 is slotted as at 21 15 upon one edge so that when the tongue 20 is projected into the opening 19, the lip 18 thereof may enter the slot 21 and lock the hasp 22 in position.

15 The latch bolt 16 has an opening 23 near 20 its end opposite the lip 18, by which the end of a key is received so that the latch bolt 16 may be pushed backwardly away from the tongue 20 in a manner presently to be more fully explained. Other openings 24 at 25 either side of the central opening 23 serves to receive the ends of the tangs 12 of the slot cover 11. The ends of the tangs 12 after being received by the openings 24, are bent over as shown in Fig. 7 and thus serve 30 to secure both the latch bolt 16 and slot cover 11, in position. Portions of the adjacent edge of the latch bolt 16 are stamped out to provide a pair of tongues 25. A spring 26 is held between the tongues 25 35 substantially as shown in Fig. 7, and the free end of the spring 26 bears against the adjacent shoulder of the housing 6 and thus serve to normally force the latch bolt 16 forwardly into engagement with the tongue 20 40 of the hasp 22.

45 A tumbler 27 is movable cross-wise of the latch bolt 16 and is slidable between the up struck portions 17 which constitute the guides previously described. The tumbler 27 includes a V-shaped portion 28 which is 50 adapted to receive the single bit of a key. The tumbler 27 is pressed into position by a spring 29, one end of which is received in a suitably U-shaped recess 30, while the other 55 end bears against an adjacent one of the up struck portions 17.

55 A cover 31 is fitted within the lock plate 3 in such a manner as to entirely close the latch bolt 16 and its cooperating parts, substantially as shown in Fig. 6. The cover 31 includes the lips or lugs 32 through the medium of which the cover 31 is secured in place by inserting the lugs 32 into recesses 32a in the adjacent portions of the flanges 5 60 of the lock plate. The cover 31 also includes flanges 33 which are received by the housing 6 and upon which the lateral edges of the latch bolt 16 slide.

An abutment 34 is bent inwardly from one of the flanges 33 of the cover 31 and is 65 adapted to be engaged by the tumbler 27 as shown in Fig. 7. When the tumbler 27 engages the abutment 34, the latch bolt 16 is locked in its forward position. By causing the retracting of the tumbler 27 from the 70 abutment 34 by inserting a suitable key and turning the same, the latch bolt 16 may be retracted from the tongue 20 of the hasp 22, by pulling upon the shank of the key and bodily moving the latch bolt 16 from such 75 engagement.

The cover 31 has openings 35 and 36 which are adapted to permit the consequent movement of the bent over tangs 12 and admit the end of the tongue 20, respectively. 80 These openings incidentally serve to lighten the cover 31.

The hasp 22 includes a pair of ears 37 which as shown in Fig. 11 rest upon the adjacent surface of attaching plate 38. A 85 tongue 39 on the attaching plate 38, is disposed between the ears 37 and is adapted to engage the hasp 22 and limit the movement thereof in one direction.

The front edge of the tongue 39 is bent 90 downwardly as shown in Fig. 11 so that a spring 40 which is held therebeneath, may not readily slip out. The ends of the spring 40 bear against steps 41 upon which other bent tongues 42 on the hasp 22 are adapted 95 to rest. It will be observed that in addition to the bearing of the spring 40 upon the adjacent step 41 that it also bears upon the side flange portion of the hasp 22. The hasp 22 is thus normally held upward and 100 away from the lock plate 3. Obviously when it is desired to lock the suitcase, the hasp 22 is pressed down upon so that the tongue 20 will enter the circular opening 8 in the pressed portion 7, where the slot 21 105 may be engaged or entered by the lip 18 of the latch bolt 16.

The operation of the device is as follows. The latch bolt 16 is normally pressed forwardly through the medium of the engagement of the leaf spring 26 which is secured upon the latch bolt 16, with the adjacent shoulder of the housing 6. The lip 18 then normally partly closes the opening 8 and is in position to be received by the slot 21 of 115 the tongue 20 when the tongue 20 is presented to the opening 8.

Upon inserting a key into the lock and by turning it in the proper direction, the tumbler 27 is caused to engage the abutment 34 120 upon one of the flanges 33 of the cover 31, and the latch bolt 16 is then prevented from moving backwardly. When it is now desired to unlock the suitcase, a key is similarly inserted in the lock and turned in the 125 proper direction to cause the retraction of

the tumbler 27 from the abutment 34. It will now be necessary to bodily pull the latch bolt 16 backwardly against the tension of the spring 26 when the hasp 22 through the medium of the spring 40, will spring upwardly and the suitcase will be unlocked.

It may again be stated that one of the essential features of the invention lies in the peculiar formation of the lock of stamped metal. It will be understood that all of the movable parts as well as the fixed parts of the lock may be stamped out of single pieces of metal and thus the manufacture of the lock may be carried out at a very low cost. It should be observed that by provision of the recesses in the adjacent flange portions of the lock plate, that the cover may be assembled or placed in position after the plate is plated or enameled. By providing this type of securing connection, the finish is not spoiled. Furthermore there are no rivets or holes to punch for rivets, or unplated parts to show through, and the plate flanges are not bent in to offer a securing means as is the case in many types of locks.

While the construction and arrangement of the device as described and illustrated is that of a generally preferred form, obviously modifications and changes therein may be made without departing from the spirit of the invention or the scope of the claims.

I claim:

1. A hasp including a fixed member having steps and a flanged tongue, a movable member having ears, an abutment adapted to engage the steps, and a spring mounted beneath the flanged tongue and engageable in the movable member at the steps for holding the movable member in an erect position.

2. A hasp comprising an attaching plate having a flanged tongue, a movable member pivotally mounted upon said attaching plate a flat spring bearing upon said movable member and engaging said flanged tongue, so that said spring will be held against displacement and will urge said movable member in one direction.

3. A device of the class described comprising a plate, said plate having a flanged tongue, a movable hasp having ears bearing upon said plate, whereby said hasp is pivotally mounted upon said plate, a flat spring bearing upon said plate and said hasp for urging said hasp in one direction, said flanged tongue engaging said spring for holding the spring in front of said ears, thereby holding said ears upon said attaching plate and preventing the accidental displacement of said spring.

4. In a device of the class described, the combination of a lock body, having a hous-

ing, a latch bolt reciprocally mounted within said housing, means for urging said bolt in one direction, means for releasably retaining said latch bolt in a set position, a cover positioned upon the rear of said lock-body, said cover having inwardly extending flanges, said flanges extending into said housing and engaging the edges of said latch bolt for holding the same in a central position, outwardly projecting lugs formed on the ends of said cover, said lock body having recesses formed therein, and said lugs fitting within said recesses for holding said cover against displacement, thus causing the operating element of the device to be inclosed in said housing.

5. In a device of the class described, the combination of a lock body, having a housing, a latch bolt reciprocally mounted within said housing, means for urging said latch bolt in one direction, upstruck portions formed upon the side portions of said latch bolt, said upstruck portions having notches formed in alinement and provided with overhanging portions, a tumbler reciprocally mounted between the notched portions of said upstruck portions, and the overhanging portions of said upstruck portions bearing upon said tumbler for holding the same against displacement, whereby said tumbler may releasably retain said latch bolt in a set position.

6. In a device of the class described, the combination of a lock body, having a housing, a latch bolt reciprocally mounted within said housing, said latch bolt having upstruck portions on its side edges, said upstruck portions having notches provided with overhanging portions, a tumbler positioned upon said latch bolt, said tumbler passing within the notches of said upstruck portions, said upstruck portions fitting upon said tumbler for holding the same against displacement, means for urging said tumbler in one direction, parallel tongues formed in the longitudinal axis of said latch bolt, a flat spring passing between said tongues and bearing upon the housing whereby said spring will be held against displacement and will urge said latch bolt in one direction, said tumbler being adapted to releasably retain said latch bolt in a set position.

7. In a device of the class described, the combination of a lock body having a housing, a latch bolt positioned within said housing, upstruck portions formed upon end of said latch bolt and having notches therein, said upstruck portions having overhanging portions with respect to said notches, a tumbler positioned upon said latch bolt and passing through said notches, said upstruck portions bearing upon said tumbler for holding the same against accidental displace-

ment, means for urging said tumbler in one direction, parallel tongues formed upon said latch bolt, a cover having inwardly extending flanges, said cover positioned upon said lock body and said flanges extending into said housing, said latch bolt riding upon said flanges, a flat spring passing between said tongues and bearing upon one of said flanges, means for urging said latch bolt in one direction, said lock body having

recesses, lugs extending from the ends of said cover and fitting within said recesses for holding said cover in a set position.

In testimony whereof I affix my signature in presence of two witnesses.

ERNEST H. SHAFF.
